(57) **CLAIM**

The ornamental design for an accessory mount as shown and described.

DESCRIPTION

FIG. 1 is a front view showing the accessory mount design;
FIG. 2 is a front view thereof with accessories attached;
FIG. 3 is a right side view thereof with accessories attached;
FIG. 4 is a left side view thereof with accessories attached;
FIG. 5 is a top view thereof;
FIG. 6 is a top view thereof with accessories attached;
FIG. 7 is a back view thereof;
FIG. 8 is a bottom view thereof;
FIG. 9 is a perspective view thereof;
FIG. 10 is another perspective view thereof; and,
FIG. 11 is an exploded perspective view thereof.

The broken lines showing the accessories depict environmental subject matter that forms no part of the claimed design.

All other broken lines in the drawings depict portions of the accessory mount that form no part of the claimed design.
